UNITED STATES PATENT OFFICE.

JULES VUILLAUME AND FRITZ MARBACH, OF PARIS, FRANCE, ASSIGNEES TO THE NATIONAL CASH REGISTER COMPANY, OF DAYTON, OHIO, A CORPORATION OF OHIO, (INCORPORATED IN 1906.)

CASH-REGISTER.

1,153,361.

Specification of Letters Patent. Patented Sept. 14, 1915.

Application filed December 18, 1911. Serial No. 666,432.

To all whom it may concern:

Be it known that we, JULES VUILLAUME, Belgian subject, and FRITZ MARBACH, Swiss citizen, both residing at Paris, France, have invented certain new and useful Improvements in Cash-Registers, of which we declare the following to be a full, clear, and exact description.

This invention relates to accounting machines and more particularly to the recording mechanism thereof.

The principal object of this invention is to provide the recording mechanism with an invariably movable impression mechanism, the latter having an operating mechanism which has a variable movement.

It is a desirable feature in check issuing machines to list the various items purchased by a customer and the total of said items upon a check which is given to the customer as a receipt for the purchase and it is a further object of this invention to provide means for severing the check strip as an accompaniment to the recording or listing of the totals.

Mechanism is provided for accumulating the total of the items as they are listed upon the check strip and another object of this invention is to provide a "total" manipulative device, which, when operated, controls means for severing the check strip and disabling the accumulating mechanism as an accompaniment to the recording of the total.

A further object of this invention is to provide an invariably movable check feeding mechanism constructed to impart a variable feed to the check strip so that when items are listed upon the check strip, the said strip will be fed equal distances and when the total is recorded the strip will be fed a greater distance, thereby separating the total from the listed items so that said total may be readily distinguished from the items.

With these and incidental objects in view, the invention consists in certain novel features of construction and combinations of parts, the essential elements of which are set forth in appended claims, and a preferred form of embodiment of which is hereinafter described with reference to the drawings which accompany and form part of the specification.

Figure 1 is a side elevation of the record-

ing mechanism of a machine of a well known type with the improvements applied thereto. Fig. 2 is a detail view of the setting devices for the type carriers. Fig. 3 is an enlarged detail view of the mechanism for feeding the check strip to the type carriers. Fig. 4 is an enlarged detail view of the platen and operating mechanism therefor. Fig. 5 is a plan view of a check having a series of items and the total thereof listed thereon. Fig. 6 is a view somewhat similar to Fig. 3 showing the check strip fed to a position to have an item printed thereon. Fig. 7 is a view somewhat similar to Fig. 4 showing the platen operating mechanism in position for operating the platen for the purpose of listing items upon the check strip. Fig. 8 is a partial central transverse sectional view through a well known type of machine to which these improvements have been shown applied. Fig. 9 is a detail view of the total manipulative device and co-operating mechanism for disabling the accumulator. Fig. 10 is a transverse sectional view taken along the side of the bank of keys containing the total manipulative device or key and showing the mechanism under the control of said total manipulative device or key. Fig. 11 is a detail view showing a modification of the check feeding and platen operating mechanism.

For the sake of illustration these improvements have been shown applied to a type of machine well known on the market and exemplified in the patents to Cleal and Reinhard, No. 580,378, issued April 13, 1897, and to Thomas Carroll, No. 765,767, issued July 26, 1904. In the former patent the principal movement of the machine is clearly shown and described, while in the latter patent the recording mechanism to which the present improvements have been applied is shown. The type of machine shown in said patents is provided with a plurality of banks of amount keys 1, which control the differential movement of segments 2 (Fig. 8) that are loosely mounted upon a rock shaft 3. These segments 2 mesh with intermediate gears 4 which in turn actuate the accumulating mechanism 5 and the indicators (not shown) as is well understood in the art. Previous to the movement of the intermediate gears 4 by the segments 2, the accumulating mechanism 5 is coupled to the in-

termediate gears 4 by double-width pinions 6 which are supported by arms 7 extending upwardly from a rock shaft 8. This shaft is rocked, previous to the displacement of 5 the intermediate gears 4, by a pitman 9, the forward end of said pitman being provided with a notch 10 into which normally rests a pin 11 projecting from an arm 12 extending downwardly from said shaft. The rearward end of the pitman is provided with a roller 13 which plays in a groove 14 of a disk 15 secured to the main operating shaft 16. Upon the rotation of the shaft 16 the pitman 9 will be moved forwardly, by which 10 movement the pinions 6 will be carried into position to couple the accumulator to the intermediate gears 4, all of which is well known in the art and fully shown and described in the aforementioned Cleal and 15 Reinhard patent, reference to which may be had for a further detailed description of 20 said mechanism.

Each of the segments 2 is provided with a roller 17, which plays in an elongated slot 25 18 formed in an arm 19 secured at its lower end to one of a series of nested sleeves 20. These sleeves at their outer ends (Fig. 2) have secured thereto segments 21, only one of which is shown, which segments mesh 30 with pinions 22 secured to the inner end of nested sleeves, which sleeves at their outer end are provided with type carriers 24, all of which is fully shown and described in the aforementioned Carroll patent.

35 As shown in Fig. 1, the type carriers 24 are provided with duplicate sets of type for recording upon a sales strip 25 and a check strip 26 at each operation of the machine. The machine, as shown, is arranged 40 to be operated by a crank handle 27 which is suitably geared to a large intermediate gear 28 that in turn will, through the intervening gear 29, impart a complete rotary movement to the shaft 16, and to a pair of feed rollers 45 30 for the check strip (Figs. 3 and 5) located near the bottom of the machine in juxtaposition to the type carriers 24. The lower feed roller is mounted upon a hub 31 which has projecting therefrom eccentric 50 bearings 32. The upper feed roller is provided with feeding flanges 33 and 34 of different lengths and a spring pressed feeding pawl 35, the latter being mounted upon the roller 30 intermediate the flanges 33 and 34.

55 One of the eccentric bearings 32 of the hub 31 has secured thereto a downwardly extending arm 36 (Figs. 3 and 6), which, at its lower end, is provided with a recess 37 into which extends a pin 38 projecting from 60 the lower end of an arm 39, the latter being pivoted as at 40 to the frame work of the machine. Secured to this arm 39 and extending upwardly therefrom is an arm 41, which, at its extreme upper end, is provided 65 with a roller 42 that co-operates with a lock-

ing flange 43 projecting from a disk 44 secured to a shaft 45. The pin 38 which projects from the lower end of the arm 39, has secured thereto the forward end of a link 46, the rearward end of which is secured to 70 an arm 47, which is rigid to a shaft 48 that extends through the machine and has projecting therefrom at its left hand end (Fig. 10) an upwardly extending arm 49. To this arm is secured the rearward end of a link 75 50, the forward end of which is slotted so as to straddle the rock shaft 8 and be supported thereby. When the above described parts are in the positions shown in Figs. 3 and 10, a spring 51, connected to the forward end of the link 50 and to a pin 52 projecting from the frame work of the machine, is under tension so that when the locking flange 43 is rotated in the direction of the arrow shown in Fig. 3, the roller 42 80 will move through the opening 53 formed in said flange when the latter is rotated far enough to present said opening to the roller 42. The timing of the release of the roller 42 is such that previous to the release thereof the feeding flange 33 of the roller 30 will have fed the check strip 26 in the position to have an item listed thereon. Upon the release of the roller 42, the spring 51 (Fig. 10) will draw the link 50 forwardly and through arm 49 rock the shaft 48 in the direction of the arrow shown in Figs. 3 and 10. This rocking of the shaft will, through arm 47, link 46 and arm 36 secured to one of the eccentric bearings 32, rock said bearing 90 95 so as to lower the hub 31 of the lower feed roller 30 as shown in Fig. 6. In this position the lower feed roller 30 will be out of operative relation with the flanges 33 and 34 of the upper feed roller, but owing to the 100 length of the tooth of the feed pawl 35 carried by the upper roller 30, will not be out of operative relation with said feed pawl. 105 Secured to the lower feed roller 30 is a disk 54 provided with a cam groove 55 in which plays a pin 56 extending from an operating lever 57 for the platen frame 58. At its rear end this lever is pivoted to the frame work as at 59 and at its forward end is pivoted to the platen frame 58. The frame 58 110 has yieldingly mounted thereon a platen 60 provided with pins 61 which extend through a portion of the platen frame. Each of these pins, only one of which is shown, is surrounded by a coil spring 62 115 which normally holds the platen 60 in the position shown in the drawings. The cam slot 55 formed in the disk 54 is of a slightly greater width than the roller 56 which plays therein, this construction being for the purpose of permitting the disk to be moved independently of the operating lever 57 for the platen when the lower feed roller 30 is moved out of co-operative relation with the flanges of the upper feed roller. 120 125 130

Previous to the recording of the first one of a series of items, the parts are in the position shown in Figs. 3 and 4, in which position the flange 33 of the upper feed roller 5 upon the operation of the machine feeds the check strip 26 forwardly into position to receive the first impression. Immediately after the feeding of this check strip by the flange 33 and the lower roller 30, the slot 53 10 formed in the locking flange 43 presents itself to the roller 42 projecting from the upper end of the arm 41, at which time the spring 51 (Fig. 10) will draw the link 50 forwardly and rock the shaft 48 in the direction of the arrows (Figs. 3 and 10) and thereby move the lever composed of arms 39 and 41 so that at the end of the operation the parts will be in the position as shown in Figs. 6 and 7 of the drawings. The shape 15 of the cam groove 55 of the disk 54 is such that it does not operate the platen lever 57 until near the end of the operation of the machine and as the disk 54 is lowered with the lower feed roller 30 immediately after 20 the check is fed into position to have recorded thereon the first item, it will be seen from Fig. 7 of the drawings that the operating lever 57 and platen carrying frame 58 will not have imparted thereto by the cam portion 25 of the groove 55 a movement as great as would be imparted thereto if the parts remained in the position shown in Figs. 3 and 4. The purpose of this variable movement of the operating lever 57 and the 30 platen frame 58 is to permit the entry of items upon the check strip without severing said strip by a knife 63 carried by the platen frame 58. In the elevation of the platen frame for the purpose of recording the 35 items, the knife 63 carried thereby will be raised to the lower edge of the slot 64 formed in the stationary knife 65 through which the check strip 26 is fed, this movement of the platen frame 58 being sufficient for the 40 platen 60 to take an impression from the type carriers 24. During the listing of other items with the parts shown in Figs. 6 and 7, the check strip will be gripped by the tooth of the pawl 35 and the lower feed 45 roller and thereby be fed slightly at each operation into position to have other items listed thereon.

After the desired number of items have been entered in the accumulator and recorded upon the check strip, the amount keys which correspond to the amount of the total and also a total manipulative device 66 (Figs. 9 and 10) will be depressed. This operation of the total manipulative device 66 (Fig. 9) will rock a lever 67 and, through link 68, rock a lever 69 into the position shown by dotted lines in said figure. The lever 69 has projecting from the upper end thereof a flange 70 which is brought into 50 coöperative relation with a camming flange 71 secured to a plate 72 fastened to the rock shaft 3. The lever 69 is secured to a sliot transverse shaft 73, which has projecting therefrom a forwardly extending finger 74 (Fig. 8), which is brought into contact with the bottom of an arm 75 loosely mounted upon the shaft 73 when said shaft 73 is rocked upon the depressing of the "total" key 66. Upon the operation of the machine by the crank handle 27, the shaft 3 will first 75 be rocked in the direction of the arrow (Fig. 9) which causes the flange 71, through flange 70, to rock the arm 69 farther rearwardly. This farther movement of the arm 69 will, through the shaft 73 and finger 74 rock the 80 arm 75 (Fig. 8) in a clockwise direction. To the forward end of this arm 75 is connected one end of a link 76, the upper end of which is connected to the pitman 9. From this it will be seen that as the arm 75 85 is rocked, as above described, the pitman 9 will be so elevated as to carry the recess 10 formed in the forward end thereof above the pin 11 projecting from the arm, so that when said pitman 9 is moved forwardly by 90 the cam groove 14 of the disk 15 it will not rock the shaft 8, and thereby prevent the coupling, through the double width pinions 6, of the accumulating mechanism 5 and the gears 4. 95

The depression of the total key 66 moves a plate 77 (Fig. 10) rearwardly against the tension of its spring 79. This rearward movement of the plate 77 by the total key 66 will bring the end of a slot 78, formed in the rearward end of plate 77, into contact with a pin 80 projecting from the link 60 which link, as previously described, has been moved forwardly by its spring 51 upon the entering of the items. This rearward movement of the plate 77 will also bring a roller 81 thereon into the path of a camming projection 82 formed on an arm 83 secured to the rock shaft 3. The cam portion 82 of the arm 83 is so timed as to engage with the roller 81 immediately upon the slot 53 (Fig. 6) of the locking flange 43 presenting itself to the roller 42 projecting from the arm 41, so that as said plate 77 is cammed rearwardly by the camming portion 82 and roller 81 it will, through pin 82, cam the link 50 rearwardly, which link, through arm 49, will rock the shaft 48 in the direction as shown by the dotted arrow (Figs. 6 and 10). This rocking of the shaft 48 will, through the arm 47, link 46 and arms 39 and 41 carry the roller back through the opening 53. This rocking of the shaft 48 will also, through the arms 47 and 36 and link 46 connecting said arm, rock the eccentric bearings 32 so as to carry the lower feed roller into position to be in coöperative relation with the feeding flange 34 of the upper feed roller, so that upon the continued operation 105 of the machine the check will be fed a 110

115

120

125

130

greater distance than when the items are listed. After the check has been fed the cam groove 55 formed in the disk 54 which now has assumed the position shown in Fig. 4, 5 will rock the operating lever 57 and, through the frame 58, carry the platen 60 into contact with the type carriers 24. Owing to the location of the roller 56 projecting from the operating lever 57 relative to 10 the operating portions of the cam groove 54 it will be obvious that the said lever and the platen frame will be given a greater degree of movement than when the items are listed. This greater degree of movement of 15 the platen frame is permissible owing to the platen 60 being yieldingly mounted thereon. During this movement of the frame 58 the knife 63 carried thereby will pass above the opening 64 formed in the stationary knife 65 and thereby sever the check strip so that the severed portion containing the items and the total thereof may be handed to the customer as a receipt for the purchase. The knife 63 is mounted upon pins 84 projecting 20 from the platen frame 58 and said knife is held yieldingly in engagement with the stationary knife by springs 85 which surround the pins 84. The total manipulative device 66 controls one of the type carriers so as to 25 print a "T" character (Fig. 5) in connection with the total to further identify said total. The "H" character shown on the check opposite the items identifies the clerk making the sale.

30 An inking ribbon 86 is provided, which ribbon is fed in any suitable manner between the type carriers and the platen.

35 It will be seen that in the machine, as thus described, a single impression is made at each operation, and that the strip may be severed after any desired number of operations of the machine. This is of value in permitting the printing of totals. The platen construction described is, however, 40 useful in other relations. For example, the use of cash registers which deliver a so called stub-check is well known. In such a use duplicate impressions are taken from the type carriers at each operation of the machine, the check being, if desired, perforated between the impressions, whereby its parts 45 may be easily severed and one be retained by a cashier, the other being delivered to the customer.

50 Fig. 11 shows the construction of a yielding platen already described, as applied to a stub check machine. In this form of device the lower feed roller 30 is always in position to coöperate with the flanges of the upper feed roller, the said flanges being so located 55 as not to feed the check during the taking of impressions thereon. It will be noted that in this form, the groove 55 formed in the disk 54 is provided with two camming portions which operate the platen twice dur-

ing each rotation of the disk 54 to take impressions from the type carriers, it being noted that the cam portion last to operate the platen lever 57 is of greater depth than the preceding portion so as to give the 70 platen frame 58 a greater throw in order to sever the check by the knife 63 carried by said frame. The platen 60 is yieldingly mounted in the frame 58 in the same manner as disclosed in Figs. 3, 4, 6 and 7.

75 It will be seen that in both the main construction and the stub check form the platen 60 receives an invariable movement on taking impression from the type carriers 24, while the platen frame 58 and the operating 80 lever 57 therefor are given variable movements. Applicants believe they are the first in the art to provide such a construction and they desire to claim the same broadly 85 without reference to the particular mechanism employed.

90 While the form of mechanism herein shown and described is admirably adapted to fulfil the objects primarily stated, it is to be understood that it is not intended to confine the invention to the one form of embodiment herein shown and described, as it is susceptible of embodiment in various forms, all coming within the scope of the 95 claims which follow.

95 What is claimed is:

1. In a machine of the class described, the combination with a type carrier, of an operating device, with means for giving, it 100 movement of variable extents, and a platen given invariable movements against said type carrier by the variable movements of said operating device, whereby to take a plurality of impressions from said type carrier on a record material.

105 2. In a machine of the class described, the combination with a type carrier, of a variably movable frame and a platen yieldingly mounted on said frame for taking a plurality of impressions from said type carrier 110 upon a check strip, and an operating mechanism for said platen frame.

115 3. In a machine of the class described, the combination with a type carrier, of a platen invariably movable for taking a plurality 120 of impressions therefrom upon a check strip, a variably movable operating mechanism for said platen, and means for feeding the check strip between the taking of impressions thereon.

125 4. In a machine of the class described, the combination with a type carrier, of a variably movable frame and a platen yieldingly mounted on said frame for taking a plurality 130 of impressions upon a check strip from said type carrier, an operating mechanism for said platen frame, and means for feeding the check strip between the taking of impressions thereon.

135 5. In a machine of the class described, the

- combination with a type carrier, of a platen invariably movable for taking a plurality of impressions therefrom upon a check strip, a variably movable operating mechanism for said platen, and means controlled by the operating mechanism for severing the check strip when the said mechanism receives its greatest degree of movement. 6. In a machine of the class described, the combination with a type carrier, of a variably movable frame and a platen yieldingly mounted on said frame for taking a plurality of impressions upon a check strip from said type carrier, an operating mechanism for said platen frame, and means movable with the platen frame and so constructed as to sever the check strip when the platen frame receives its greatest degree of movement. 7. In a machine of the class described, the combination with a type carrier, of means for feeding a check strip thereto, a variably movable frame and a platen yieldingly mounted on said frame for taking a plurality of impressions upon the check strip from said type carrier, an operating mechanism for said platen frame, and a knife carried by the platen frame and constructed to sever the check strip when the platen frame receives its greatest degree of movement. 8. In a machine of the class described, the combination with a set of type carriers, means for feeding a check strip thereto, a platen for recording upon the check strip from the type carriers a series of items and the total thereof, a variably movable operating mechanism for said platen, and means for severing the check strip when the total is recorded. 9. In a machine of the class described, the combination with a set of type carriers, means for feeding a check strip thereto, a platen for recording upon the check strip from the type carriers a series of items and the total thereof, a variably movable operating mechanism for said platen, and means controlled by the operating mechanism for severing the check strip as an accompaniment to the recording of the total. 10. In a machine of the class described, the combination with a set of type carriers, means for feeding a check strip thereto, a variably movable frame and a platen yieldingly mounted on said frame for recording upon the check strip from the type carriers a series of items and the total thereof, an operating mechanism for the platen frame, and a knife carried by the platen frame and constructed to sever the check as an accompaniment to the recording of the total. 11. In a machine of the class described, the combination with a set of type carriers, of a platen for recording upon a check strip from the type carriers a series of items and the total thereof, and a pair of feed rollers having an invariable movement and constructed to feed the check strip a greater distance when the total is recorded than when the items are recorded. 12. In a machine of the class described, the combination with a type carrier, of a platen for taking a plurality of impressions therefrom upon a check strip, and a pair of feed rollers having an invariable movement and constructed to feed the check strip variable distances. 13. In a machine of the class described, the combination with a set of type carriers, of a platen for recording items and the total thereof upon a check strip from said type carriers, a pair of feed rollers having an invariable movement and constructed to feed the check strip a greater distance when the total is recorded than when the items are recorded, and means for severing the check strip as an accompaniment to the recording of the total. 14. In a machine of the class described, the combination with a set of type carriers for recording upon a check strip items and the total thereof, of manipulative devices for determining the amounts of the items and totals to be recorded upon the check strip, mechanism for accumulating the total as the items are recorded, means for severing the check strip upon the recording of the total, and means for disabling the accumulating mechanism as an accompaniment to the recording of the total. 15. In a machine of the class described, the combination with a set of type carriers for recording upon a check strip items and the total thereof, of manipulative devices for determining the amounts of the items and the total recorded upon the check strip, mechanism for accumulating the total as the items are recorded, a total key, and means under the control thereof for severing the check strip and for disabling the accumulating mechanism as an accompaniment to the recording of the total. 16. In a machine of the class described, the combination with a set of type carriers, of a platen for recording items and the total thereof upon a check strip from said type carriers, a pair of feed rollers constructed to automatically feed the check strip a greater distance when the total is recorded than when the items are recorded, and means for severing the check strip as an accompaniment to the recording of the total. 17. In a machine of the class described, the combination with a set of type carriers, of a platen for recording upon the check strip from the type carriers a series of items and the total thereof, and a pair of feed rollers having an invariable movement and constructed to automatically feed the check strip a greater distance when the total is recorded than when the items are recorded.

18. In a machine of the class described, the combination with a type carrier, of a platen for taking a plurality of impressions therefrom upon a check strip, and a pair 5 of feed rollers having an invariable movement and constructed to automatically feed the check strip variable distances.
19. In a machine of the class described, the combination with a set of type carriers, 10 of a platen for recording items and the total thereof upon a check strip from said type carriers, a pair of feed rollers having an invariable movement and constructed to automatically feed the check strip a greater 15 distance when the total is recorded than when the items are recorded, and means for severing the check strip as an accompaniment to the recording of the total.
20. In a machine of the class described, 20 the combination with a set of type carriers, of a platen for recording upon a check strip from type carriers a series of items and the total thereof, a pair of feed rollers having an invariable movement, a disk rigid 25 with one of said rollers and having a projection for feeding the check strip when a total is recorded on said strip, a pawl carried

by said roller for feeding the check strip when an item is recorded on the strip, and means for selectively rendering either said 30 projections or said pawl effective.

21. In a machine of the class described, the combination with a set of type carriers, of a platen for recording upon a check strip from the type carriers a series of items and 35 the total thereof, a pair of feed rollers having an invariable movement, an eccentric on which one of the rollers is mounted, a plate rigid with said eccentrically mounted roller and having a projection for feeding the 40 check strip when a total is recorded on said strip, a pawl carried by said roller for feeding the check strip when an item is recorded thereon, and manipulative means for controlling the eccentric bearing to render either 45 said projection or said pawl effective.

In testimony whereof we affix our signatures in the presence of two witnesses.

JULES VUILLAUME.
FRITZ MARBACH.
